[57] **CLAIM**

The ornamental design for a mat for pet feeding dish, as shown and described.

DESCRIPTION

FIG. 1 is a perspective view of a mat for pet feeding dish showing our new design;

FIG. 2 is a top plan view thereof;

FIG. 3 is a side elevational view thereof, the opposite side elevational view being the same;

FIG. 4 is an end elevational view, the opposite end elevational view being the same;

FIG. 5 is a bottom plan view thereof; and,

FIG. 6 is a cross sectional view taken on line 6—6 of FIG. 2.
